UNITED STATES PATENT OFFICE.

SAMUEL M. SCHMELTZER, OF CANTON, OHIO, ASSIGNOR TO THE CANTON MACHINE AND MANUFACTURING COMPANY, OF CANTON, OHIO.

SHEET-METAL-PIPE FORMER.

SPECIFICATION forming part of Letters Patent No. 728,178, dated May 12, 1903.

Application filed February 6, 1902. Serial No. 92,878. (No model.)

To all whom it may concern:

Be it known that I, SAMUEL M. SCHMELTZER, a citizen of the United States, residing at Canton, in the county of Stark and State 5 of Ohio, have invented a new and useful Sheet-Metal-Pipe Former, of which the following is a specification.

My invention relates to pipe-forming machines in which sheet metal, having been 10 edged, is formed around a mandrel and the turned edges locked preparatory to being grooved; and the object of my improvement is to provide means for completing the forming and locking of the turned edges which 15 can be adapted to various-sized mandrels and pipes. I attain this object by the mechanism illustrated in the accompanying drawings, in which—

Figure 1 is a plan view of the entire machine; Fig. 2, a longitudinal vertical section of the same; Fig. 3, a cross-section on the line 3 3, Fig. 1; Fig. 4, a fragmentary cross-section showing the first operation in the forming; Fig. 5, a similar view showing the 25 second operation; Fig. 6, a similar view showing the forming completed, and Fig. 7 a similar view showing the edges locked.

Similar numerals refer to similar parts throughout the several views.

In the embodiment of my invention as illustrated the frame consists of two similar members 1 and 1^a, connected by the frame-rods 2. The block-girder 3 is supported by the brackets 4 between the frame members in the lower 30 part in the middle line. Above the block-girder 3 is located the vertically-movable block-plate 5, the similar end brackets 6 of which are guided by the flanges 7 and 7^a on the frame members. Connecting the block-girder and the block-plate are the toggle-levers 8, the respective bars of which are pivoted to the girder below and the plate above and the common joints to the block-actuating 35 bar 9.

The blade-girders 10 and 11 are supported on the top of the frame members by the similar brackets 12, which are movable sidewise toward and from the middle line. Connecting the blade-girders, respectively, and the 40 frame are the toggle-levers 13 and 14, the respective bars of which are pivoted to the outer

parts of the frame members and the blade-girders, respectively, and the common joints to the blade-actuating bars 15 and 16, respectively.

The round mandrel 17 is horizontally located in the middle line and is supported on the frame member 1 by the bracket 18 and on the frame member 1^a by the grooved roller 19.

On the block-plate 5 is attached the forming-block 20, which has the longitudinal semicircular groove 21 in its upper side of slightly larger diameter than the mandrel. On the inner side of the girder 10 is attached the forming-blade 22, which has its upper 65 side beveled, so as to form the sharp projecting edge 23, and on the inner side of the girder 11 is attached the locking-blade 24, which has its projecting edge 25 blunt or slightly rounded. These blades are preferably made of angle-iron, and the attaching sides are provided with the slots 26, through which are passed the attaching-bolts 27, thus giving a vertical adjustment. The lower sides of the respective blades are formed flat and 70 horizontal.

The three several cams 34, 35, and 36 are mounted on the cam-shaft 37. The cam 34 rotates in the frame 38, which is attached to the block-actuating bar 9. The cams 35 and 36, respectively, rotate in the frames 39 and 40, the outer bars 41 and 42, respectively, of which extend upward beyond the top of the machine-frame and also downward to a pivotal connection in the brackets 43, attached 85 to the lower part of said machine-frame member. The upper ends of the cam-frame bars 41 and 42 are respectively attached to the blade-actuating bars 15 and 16 by the compound knuckle-joints 44 and 45. The 90 several cams are similarly formed and are so located on the shaft that they will when rotated throw the respective frames successively outward from the machine-frame and then successively inward in the same order. 95 Thus the block toggle-levers 8 and the blade toggle-levers 13 and 14 are operated successively by their respective actuating-bars 9, 15, and 16.

The cam-shaft is mounted in the journal-bearings 28, which are attached on the outer side of the frame member 1, and the pul-

ley-shaft 29 is similarly mounted below the cam-shaft and carries the driving-pulley 30. Power is transmitted by means of the cog-pinion 31 on the pulley-shaft and the cog-wheel 32 on the cam-shaft. The cog-wheel is mounted on the cam-shaft by the ordinary pin-clutch 33, which is thrown into engagement by the rod 46 and automatically throws out at the end of one revolution.

10 To form and lock the turned edges of a sheet-metal pipe, the machine being in its normal position, as shown in Figs. 1, 2, and 3, and the sheet metal 47 having been cut to the proper length and width and the edges 48 and 49, respectively, flanged and turned back, the sheet is placed on the forming-block, where it is held in proper alinement by the guides 50 on either side, as shown in Fig. 3. The pin-clutch 33 is then thrown into engagement, and by the rotation of the several cams the work is done as follows: The forming-block 20 is first thrown upward by the toggle-levers 8, its groove 21 bending the sheet metal around the lower half of the mandrel,

15 with the turned edges extending upward, as shown in Fig. 4. The forming-blade 22 is then thrown inward by the toggle-levers 13, bending one side of the sheet metal over the mandrel, the blade being so adjusted vertically and in its lateral movement that its sharp edge 23 engages the angle of the turned edge 48 and its lower flat side holds the sheet metal immediately above, with the turned edge just beyond the middle line of the mandrel, as shown in Fig. 5. The locking-blade 24 is then thrown inward by the toggle-levers 14, bending the other side of the sheet metal over the mandrel, the blade being so adjusted vertically and in its lateral movement that

20 its lower flat side will carry the turned edge 49 immediately above and clearing beyond the turned edge 48, as shown in Fig. 6. The forming-block and the forming-blade are then successively thrown away from the mandrel,

25 by the reverse action of their respective toggle-levers, and the turned edge 48 springs up and engages and locks with the turned edge

49, as shown in Fig. 7, after which the locking-blade 24 is thrown away from the mandrel to its normal position, when the machine 50 stops, the cam-shaft having completed its one revolution, which leaves the formed and edge-locked pipe 51 free to be grooved on the mandrel or removed from its free end 52, as may be desired.

55 By my construction of the forming and locking blades the same can be adapted by vertical adjustment for making various-sized pipes with the correspondingly-sized mandrels and forming-blocks.

60 I am aware that sheet-metal ware has been formed on a mandrel with a forming-block below and blades operated from the sides above the mandrel, and I do not claim these elements broadly; but I am not aware that 65 such blades have been shaped or operated in the manner and for the purpose I specify; neither do I claim as my invention the particular mechanism illustrated in my drawings for operating the forming blocks and 70 blades.

What I claim as my invention, and desire to secure by Letters Patent, is—

75 In a sheet-metal-pipe former, the combination of a mandrel, a forming-block below and a sharp-edged forming-blade on one side and a locking-blade on the other side above said mandrel, the respective blades being vertically adjustable and having their lower sides substantially flat and horizontal, with means 80 for successively actuating said forming-block upward against the mandrel and the forming and locking blades inward and respectively above and beyond the middle line of the mandrel, and then successively away from said 85 mandrel, substantially as and for the purpose specified.

In testimony whereof I have signed my name to this specification in the presence of two subscribing witnesses.

SAMUEL M. SCHMELTZER.
